UNITED STATES PATENT OFFICE.

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT.

DENTAL PLATE BRUSH.

Application filed January 30, 1925. Serial No. 5,769.

My invention relates to brushes that are especially formed for cleaning dental plates, and an object of my invention, among others, is the production of a brush of this class so 5 constructed that it will readily enter the grooves in and will conform to various shapes of dental plates, whereby such plates may be readily cleaned in an extremely advantageous manner.

10 One form of brush embodying my invention and in the construction and use of which the objects herein set out, as well as others, may be attained, is illustrated in the accompanying drawings, in which—

15 Figure 1 is a plan view of a brush embodying my invention.

Figure 2 is a side view of the same.

Figure 3 is a perspective view of a dental plate.

20 Figures 4 and 5 are illustrative views showing the manner of use of the brush to clean such dental plate.

Figures 6 to 8 illustrate the manner of using the device.

25 In the accompanying drawings the numeral 6 indicates a handle that may be of any suitable shape and material, and to which handle a brush 7 is secured. This brush comprises a loop 8 at its outer end,

30 in the preferred form of construction this loop being substantially round with an opening 9 of substantial dimensions through its center. Between this circular loop and the handle there is a straight portion 10 and the

35 loop 8 is offset from a plane parallel therewith and extending through the axis of the handle, a portion 11 arranged at an oblique angle to said plane connecting said straight portion and circular loop, as shown in Figure 2 of the drawings.

In the preferred form of construction this brush is of what is known as the twisted wire type, that is the bristles are secured to a core formed of twisted wire.

40 Important features of my improved brush include the circular loop, the obliquely disposed portion 11 and the straight portion 10, irrespective of how these parts are constructed or formed, but in a preferred arrangement, and as shown herein, said brush is composed of a brush member comprising a core with bristles secured thereto that is folded at its lengthwise center into the circular loop 8, the parts extending from said loop being arranged parallel to each other and close

11 and the straight portion 10.

It will be noted that the structure as herein illustrated and described as peculiarly adapted to the cleaning of dental plates. In 60 this operation the circular looped portion 8 may be readily applied to the walls of the gum groove 12 of a dental plate 13, and the upper surface of the arch 14 will be surrounded by the loop 8 so that by swinging 65 the brush back and forth with the arch in the opening in the brush as a pivot the entire upper surface of the plate including the gum groove may be easily and quickly cleaned, and as illustrated in Figures 4 and 70 5 of the drawings, from which it will be seen that the brush fits nicely within the gum groove on the upper surface of the plate and when moved with a pivotal action, the handle being swung from side to side, the fit of 75 the brush to the upper surface of the plate will be maintained, and this will result in a very effective and thorough cleaning of the plate, the oblique portion 11 cooperating in producing the fit and also in the cleaning operation, enabling the latter to be performed 80 without obstruction from other parts of the brush structure.

The circular loop in cooperation with the oblique portion 11 also readily adapts itself 85 to the cleaning of the under surface of the plate including the arch and tongue groove 15, the brush being tipped from side to side and swung in various directions to cause it to make contact with the entire under surface of the plate. In this operation it will be seen that the oblique part 11 and the loop causes the brush to nicely fit the arch, including the tongue groove, and as shown in Figure 6 of the drawings, whereby a very effective 90 and thorough cleaning of this surface of the plate with little effort on the part of the operator may be accomplished.

The straight portion 10 and the oblique portion 11 may be employed to clean the 100 edges of the plate to which the teeth are secured, this by a movement of the brush crosswise of the teeth, lengthwise thereof or in any other direction, and as illustrated in Figures 7 and 8, from which it will be seen 105 that the oblique portion 11 in connection with the straight portion 10 causes the brush to nicely fit the groove of the plate on which the teeth are disposed and the teeth may be, therefore, very readily cleaned by moving 110

the brush with a rubbing action around the edge of the teeth and plate. By using the straight part in the manner illustrated in Figure 8 and effecting a vertical movement 5 the crevices between the teeth and at the base thereof where they enter the plate may be very thoroughly cleaned with little trouble.

While there is herein shown and described the preferred embodiment of the present invention, it is, nevertheless to be understood 10 that minor changes may be made therein without departing from the spirit and scope of the invention as claimed.

I claim—

- 15 1. In a dental plate bush, a twisted bristle carrying core formed with a substantially

closed circular loop portion, the end portions of the bristle carrying core being arranged substantially parallel, the bristles carried by the end portions being disposed in contacting relation and a handle attached to the termini of the end portions. 20

2. In a dental plate brush, a bristle carrying core formed with a substantially closed circular loop portion, the end portions of the core being arranged substantially parallel in contacting relations, both sides of the core being obliquely disposed between the loop and end portions to present the loop and end portions in different parallel planes. 25 30

HENRY CAVE.
